UNITED STATES PATENT OFFICE.

MAX ROGLER, OF DUSSELDORF, GERMANY.

CASK AND BARREL STAND.

1,026,127.

Specification of Letters Patent.

Patented May 14, 1912.

Application filed April 25, 1911. Serial No. 623,186.

To all whom it may concern:

Be it known that I, MAX ROGLER, residing at Dusseldorf, Germany, have invented certain new and useful Improvements in Cask and Barrel Stands, of which the following is a specification, reference being had therein to the accompanying drawing.

The present invention relates to a stand for casks and barrels and the like, such elements being supported in the improved stand by means of rollers allowing them to be easily turned about their axes and emptied through the bung-hole. A ladder is fitted in the stand so as to allow of being drawn out to a certain extent at both ends of the stand. This ladder serves in the first place as a means for rolling the casks and the like up on the stand, and in the second place to support receptacles into which the contents 20 of the casks are to be transferred.

In the accompanying drawings the invention is illustrated, Figures 1 and 2 representing side views of the arrangement in different operative positions, and Fig. 3, a 25 view of one of the supporting rollers on an enlarged scale.

The stand is composed of a frame *b* made of channeled iron bars, said frame being supported on legs *a*. On both side members 30 of the frame rollers *c*, connected to brackets, are arranged in pairs so as to serve as supports for the casks. A ladder *f* is slidably held between the side members of the frame *b*. This ladder is adapted to be drawn out 35 at both ends of the frame, either to serve as an incline, as shown in Fig. 1, for rolling the cask up on the stand, or to serve as a support, as shown in Fig. 2, for vessels into which the contents of the casks are to be 40 transferred. Suitable stops on the ladder prevent the same from being entirely withdrawn from the frame.

It will be seen that by making the lateral member *b*, from channel iron, I can conveniently use the groove *b'* thereof, of each lateral member *b*, to form a slideway for the ladder *f* so that when the latter is not in use it can be completely inclosed within the ends and sides of the supporting frame.

50 Casks or barrels of wood or iron are rolled up on the stand, as shown in Fig. 1 and arranged so as to be supported by the rollers *c*.

Thereupon the bung is removed from its hole and replaced by a suitable spout. When it is desired to draw from the contents of the cask, the receptacles to receive such contents are arranged, according as they are large or small, in any of the positions shown, whereupon the cask is turned on the rollers *c*, so that the transfer of the contents can take 55 place through the bung hole. This operation, as well as the placing of the cask on the stand, can easily be effected by one man alone. All kinds of liquid viscous substances, such as oil, varnish, tar and the like, 60 can be dispensed with greater facility in this manner than by means of pumps or taps. No dripping takes place, and the expenses incurred in the acquisition of taps and pumps are obviated. Since the liquid 65 runs quickly through the bung-hole, there is no need, as in the case of taps, to leave the cask alone while the liquid is running. An overflow of the liquid, owing to forgetfulness or inattention, is therefore avoided. A 70 more complete emptying of the cask can be effected through the bung-hole than through other parts of the cask, and the latter can easily be turned for that purpose to get the bung-hole at the lowest position. The casks 75 are held by the rollers in elevated position so that drip-trays and receptacles can be disposed underneath.

The cost of the improved stand is compensated for by the saving of other materials 80 and of labor which it brings about.

Having thus fully described my invention what I claim as new and desire to secure by Letters Patent of United States is:—

1. In a device of the character described, 90 the combination with a main frame of sufficient length to support at least two barrels, rotating mechanisms on said frame for supporting said barrels and permitting rotation thereof, and an element movably supported 95 on said frame and adapted to be projected from either end to form an incline on which the barrels may be rolled up on the frame or a support for a receptacle to be filled from the frame.

2. In a device of the character described, 100 the combination with a main frame provided with interior grooved portions longitudinally disposed thereon, means disposed

on said frame for rotatively supporting a
barrel, and an elongated ladder-like element
slidable in said grooves and adapted to be
projected from either end of said frame to
5 form an incline for rolling the barrels on to
the support or a support to be filled from the
barrel.

In testimony whereof I affix my signature
in the presence of two witnesses.

MAX ROGLER. [L.S.]
